UNITED STATES PATENT OFFICE.

CARL JENTZ, OF THREE RIVERS, QUEBEC, CANADA.

GAME APPARATUS.

1,302,805.

Specification of Letters Patent.

Patented May 6, 1919.

Application filed May 25, 1918. Serial No. 236,537.

To all whom it may concern:

Be it known that I, CARL JENTZ, a citizen of the United States, residing at Cape Magdelaine, Three Rivers, Province of Quebec, 5 Canada, in the county of Champlain, Province of Quebec, have invented certain new and useful Improvements in Game Apparatus; and I do hereby declare the following to be a full, clear, and exact description of 10 the invention, such as will enable others skilled in the art to which it appertains to make and use the same.

This invention is directed to the provision of a novel form of game apparatus which 15 may be employed in playing a game which is highly entertaining, which involves the elements of competition and chance, and which is highly instructive in that it develops the powers of the players to perform 20 arithmetical operations mentally with rapidity.

The apparatus includes a board or table or other form of playing field which is provided in any suitable manner with a plurality of series of spaces, holes or the like 25 suitably designated with consecutive figures and markers of any suitable form adapted to be moved along over the spaces designated by these figures in accordance with the indications of the dice thrown by the players in turn. The dice includes one die which is 30 provided with characters indicating various arithmetical operations such as addition, subtraction, multiplication and division. Preferably the die whose faces carry the arithmetical signs also has one face marked with a character such a cipher adapted to indicate that the player has the option of resorting to any one of the several arithmetical operations indicated by the other characters. The 35 sixth face of the indicator die may be blank to indicate that the player loses his throw. Such a die may be employed in conjunction with two dice of the usual type, the three 40 dice being thrown together and the figures indicated by the two dice of the usual form being treated in accordance with the indication of the third die bearing the arithmetical signs.

45 The field or table may be a board with several series of spaces or areas, those of each series being arranged in several rows and the spaces of each row being marked consecutively from 1 up to, say, 300. At 50 the beginning of each series of areas is a space constituting the starting point and

preferably suitably designated as for instance by the words "Starting field". At the end of each series of spaces is a goal which may be designated by that word.

55 In the preferred embodiment of the invention the field is rectangular and is provided with four series of numbered spaces to adapt the apparatus for use by four or any less number of players. When this form of the invention is employed the numbers of the four series are positioned so that each may be read conveniently from one of the sides of the field.

60 The invention may be embodied in apparatus differing considerably as to its structural characteristics. The form in which I prefer to embody the invention is illustrated in the drawings annexed hereto, and I shall therefore describe the apparatus with reference to these drawings, without intending, however, to limit the invention in any way to this specific form.

65 In the drawings Figure 1 is a face view of the table or board broken away in part;

70 Fig. 2 is a cross-section of an alternative form of board;

75 Fig. 3 is a perspective view of the dice of usual form employed in playing the game; and

80 Fig. 4 is a perspective view of the indicator die.

85 Referring to Fig. 1, the board or table or playing field 8 is preferably rectangular in form and consists of a multiplicity of rows 90 of areas designated by figures extending in parallel lines across the board. It will be understood that a suitable field of cardboard may be employed or that the rows of squares and the figures may be laid out upon the 95 top of a table in any suitable manner, and also that the field may have a plain surface adapted to have suitable markers of different colors advanced step by step on it, or that the areas designated by the figures may 100 have holes therein to receive pegs. This latter construction is indicated in Fig. 2 wherein the field is shown as a board 5 which may constitute a table top, and which is provided with holes 6 adapted to receive pins 7.

105 Referring now to Fig. 1 it will be noted that there are four series of rows of squares numbered consecutively from 1 to 300, that there is a starting field at the beginning of each series, that there is a goal at the end 110 of each series, that the four starting fields are located adjacent to the four corners of

the board, that the four goals are located adjacent to the four corners of the field, and that the figures of the four series are positioned so as to be readable from the four sides of the board. Referring to the row of figures at the left it will be noted that these are numbered from 1 to 31, that the squares of the fifth row to the right are numbered from 32 to 65 inclusive, and that the squares of the fourth row farther to the right are numbered from 66 to 99 inclusive, and so on. These three rows and all of the other rows of this series are preferably of the same color and a color different from those of the other rows. Similarly, the several rows constituting each of the other three series are similarly colored. The field is therefore made up of a plurality of rows of figures forming four series of rows with the squares of each of the several series distinctively colored and numbered from 1 to 300. Crosswise of the table the figures arrange themselves in rows but these rows cross the rows of the several series.

Fig. 3 shows two dice of the ordinary form having their six faces designated from 1 to 6 inclusive. In Fig. 4 the special indicator die employed in playing the game, is shown. As appears from this figure this die has one of its faces blank, has a zero on another face and has the remaining four faces designated with the arithmetical signs $+$, $-$, $\times$ and $\div$.

With this apparatus two dice of the usual form and one indicator die of the type shown in Fig. 4 are thrown by the several players in turn. The number shown by the two ordinary dice are treated in accordance with the sign displayed by the indicator die, and the markers are moved upon the field of the table in accordance with the result of this arithmetical operation. The zero on the indicator die may be made to give the player the option of selecting any one of the four arithmetical operations to be employed by him. The blank face of the indicator die may indicate that the player loses his throw.

Subject to the foregoing general directions, the apparatus may be employed for playing a game under any suitable rules which may be agreed upon. Preferably the following general directions as to the rules of the game should be observed: When the plus indication on the indicator die turns up, the sum of the numbers uppermost on the other two dice should be added and the marker moved along its appropriate course an amount indicated by the sum. Should the minus sign turn up, the marker should be moved backward an amount indicated by the sum, difference or product of the numbers shown by the two dice of the usual form as may be agreed upon. Should the multiplication sign turn up, the numbers

on the other two dice should be multiplied together and the marker moved an amount indicated by the product. Should the division sign turn up the larger number of the other two dice is multiplied by itself and this product divided by the other number and the marker should be moved an amount indicated by the quotient. When the option sign or zero turns up the player has the option of employing any one of the four arithmetical operations above referred to. This is of special value in connection with a rule that a marker must enter its goal by the exact number required to reach the goal. Thus, when the player's marker is near the goal and he throws the option sign, he has a choice of several arithmetical operations, one of which may serve his purpose of reaching the goal. When the blank side of the indicator die turns up the player loses his throw.

Lines of spaces across the board are referred to as a "field"; if one player has his marker in a certain field and another player moves his marker to a position in that field, the former player must remove his marker and start again from the "starting field".

An exception to this rule as to returning an opponent's marker to the starting field may be made in certain instances; preferably an exception is made with respect to all numbers divisible by 7. When two players advance their markers to spaces in the same field represented by a number which is divisible by 7, that would be what is known as a "closed gate", and no other player may advance his marker past this gate. A restriction may be imposed as to how such a closed gate may be opened, as for instance, by providing that it may be opened only by a player throwing a number which is divisible by 3.

A further provision may be made that any player whose marker reaches a space indicated by a number which is the square of another number, is entitled to another throw.

A game played with apparatus constructed as above described and in general in accordance with the rules above indicated, is interesting in that ample opportunity for competition is presented and in that the element of chance is adequately involved; in addition to this, however, is the fact that the game is of great value in that it develops the powers of the players to perform arithmetical calculations mentally and quickly. It is particularly useful, therefore, as a game for the young; for children who are quite young the rules may be considerably simplified from those above indicated, as for instance by utilizing only one of the four mathematical operations.

It will be understood that the construction which I have herein illustrated and described is that which I prefer to employ but

that the invention is not limited with respect to the structural features of the parts employed, as apparatus of various forms employing the principles of the invention may 5 be provided. All such modification of the construction above indicated I consider as within the scope of my invention and I aim to cover them by the terms of the claims appended hereto.

10 I claim:

1. Game apparatus comprising the combination of a plurality of series of spaces designated by consecutive numbers and a plurality of dice one of which has the signs 15 of arithmetical operations displayed upon its faces.

2. Game apparatus comprising the combination of a game board provided with a plurality of parallel rows of spaces designated by consecutive numbers, each of the 20 said rows consisting of a plurality of sections and the several sections of each row being indicated by a distinctive color, and a plurality of dice, one of which has the 25 signs of arithmetical operations displayed upon its faces.

3. Game apparatus comprising the combination of a plurality of series of spaces designated by consecutive numbers and a plurality of dice, one of which has the 30 signs of the operations of addition, subtrac-

tion, multiplication and division on four of the faces, has an option side upon a fifth face, and has the sixth face blank.

4. Game apparatus comprising the combination of a game board provided with a plurality of parallel rows of spaces designated by consecutive numbers, each of the said rows consisting of a plurality of sections, and the several sections of each row 35 being indicated by a distinctive color, and a plurality of dice, one of which has the signs of the operations of addition, subtraction, multiplication and division on four of the faces, has an option sign upon a fifth 40 face, and has the sixth face blank.

5. Game apparatus comprising the combination of a game board having a multiplicity of squares marked off thereon in rows extending both longitudinally and transversely, the several longitudinal rows being divided into groups, each of several series of rows consisting of one row from each group being distinctively colored and the squares in each of the similarly colored rows being 50 numbered consecutively and having a starting field at one end and a goal at the other and a plurality of dice one of which has the 55 signs of arithmetical operations displayed upon its faces.

In testimony whereof I affix my signature.

CARL JENTZ.
